PUMP

Howard S. Bancroft, Sharon, Pa.

Application March 7, 1946, Serial No. 652,634

6 Claims. (Cl. 103—157)

1

This invention relates to pumps, and, more particularly, to pumps including pistons having a combined rotary and reciprocating action with a port type valving action.

It is the general object of my invention to provide an improved pump or compressor and characterized by simplicity of design, inexpensiveness of structure, high efficiency, and long life with a minimum of maintenance.

Another object of my invention is the provision of a pump having a piston which is given a combined rotary and reciprocating motion by rugged and positive, but simple, mechanism.

Another object of my invention is to provide an improved valving action in a pump and characterized by a rotary cup which covers and uncovers the valve ports.

Another object of my invention is the provision of a pump design which is particularly adapted to be built with one or more cylinders and in any desired capacity.

Another object is to provide a pump having very high volumetric efficiency resulting from a minimum head clearance and unusual valve structure.

The foregoing objects of my invention, and other objects which will become apparent as the description proceeds, are achieved by a pump including a cylinder, a piston, means for simultaneously rotating and reciprocating the piston in the cylinder, a valve cup rotatably mounted in the head end of the cylinder and slidably receiving the head end of the piston, a spline connection between the cup and piston whereby the cup is rotated without reciprocation by the piston, inlet and exhaust ports in the head of the cylinder, and a port in the cup adapted to register with the inlet and exhaust ports in timed relation with the reciprocation of the piston.

For a better understanding of the invention, reference should be had to the accompanying drawings, wherein Fig. 1 is a vertical sectional view parallel to the axis of the crankshaft and taken through one embodiment of a pump incorporating the principles of the invention; Fig. 2 is a vertical cross-sectional view taken on line II—II of Fig. 1; Fig. 3 is a plan view of the head end of the cylinder with the head removed, as taken on line III—III of Fig. 1; Fig. 4 is a bottom plan view of the cylinder head; Fig. 5 is a side elevation of a modified manner of driving the piston; and Fig. 6 is a view similar to Fig. 5 but taken at right angles thereto.

In the drawings, the numeral 10 indicates a cylinder slidably and rotatably receiving a piston

12 in the form of a solid cylindrical body. The piston is reciprocated by a crank 14 which slidably and rotatably carries a block 16 on its crank arm bearing, the block 16 rotatably receiving a pin 18 which is fastened rigidly in the piston 12. A nut 20 and locking cotter key hold the block 16 on the pin 18.

The pin is simultaneously rotated as it is reciprocated, and this is achieved by the provision of a circular camway 22 in the piston which camway slidably engages with a roller cam 24 rotatably supported in fixed relation on a threaded plug 26 carried by the cylinder 10. From Figs. 1 and 2, it will be recognized the shape of the camway 22 is such that reciprocation of the piston will also cause rotation thereof. The piston 12 is free to rotate inasmuch as the pin 18 turns freely in the block 16, and during the rotation of the piston the block 16 slides back and forth on the unusually long connecting rod bearing of the crankshaft 14.

As shown in Figs. 5 and 6, an alternate manner of driving the piston 12 is to form it with a slot 50 which slidably receives a cross head 52 secured to a shaft 54. The shaft 54 is held in suitable bearings (not shown) and is adapted to be rotated by a motor. The rotation of the shaft 54 rotates the piston which is reciprocated by the roller cam 24 engaging in the camway 22.

Secured to the end of the cylinder 10, as by bolts 30, is a head 32 which is provided with arcuate ports 34 and 36, for intake and exhaust respectively. Positioned between the head 32 and the cylinder 10 is a cup 40, which is carried in a recess 42 in the cylinder so that the cup may rotate but is held against movement axially of the cylinder. The inside of the cup forms a continuation of the cylinder bore and slidably receives the piston.

The piston 12 serves to rotate the cup 40, and this is achieved by providing a key and spline connection 44 between the two whereby the cup is rotated as the piston turns although the piston is reciprocating and not the cup.

The closed end of the cup is formed with a valve port 46 which alternately registers with the intake and exhaust ports 34 and 36 as the cup is rotated and the piston is reciprocated, all as will be understood, to provide the positive displacement pumping action as the crank shaft 14 is rotated. Of course, any suitable prime mover is connected to the crank shaft 14 to effect rotation thereof.

Lubrication of the working parts of the apparatus may be provided for by forced feed, splash,

or in other known ways, and this forms no part of the present invention.

From the foregoing, it will be recognized that the objects of my invention have been achieved in the provision of a relatively inexpensive, rugged and simple mechanism characterized by high efficiency, long life and low maintenance. Tolerances are not critical in manufacture, and lie well within production standards, all without necessitating the use of piston rings or other sealing means. The pump provided can be utilized to pump gases or liquids of substantially any known character, and if the intake and exhaust ports are reversed the pump can be operated as a compressed air, steam or like motor.

While in accordance with the provisions of the patent statutes, I have specifically illustrated and described one best known form of my invention, it should be particularly understood I am not to be limited thereto or thereby but that the scope of my invention is defined in the appended claims.

I claim:

1. Apparatus of the type described including a cylinder, a piston slidably received in the cylinder, a crankshaft having an extra wide connecting rod bearing, a block slidably and rotatably carried on the bearing, a pin rigidly secured to the piston and rotatably secured to the block, cam and cam way means between the piston and cylinder for rotating the piston when the piston is reciprocated by the crank shaft, a head on the cylinder having intake and exhaust ports therein, a cup supported between the head and cylinder for rotary but non-axial movement, the inside of the cup forming a continuation of the bore of the cylinder and slidably receiving the head end of the piston, a spline and key connection between the piston and cup whereby rotation of the piston effects rotation of the cup, said cup having a port in its end and alternately registering with the intake and exhaust ports in timed relation with the reciprocation of the piston.

2. Apparatus of the type described including a cylinder, a piston slidably received in the cylinder, means for simultaneously rotating and reciprocating the piston in the cylinder, a head on the cylinder having intake and exhaust ports therein, a cup supported between the head and cylinder for rotary but non-axial movement, the inside of the cup forming a continuation of the bore of the cylinder and slidably receiving the head end of the piston, a spline and key connection between the piston and cup whereby rotation of the piston effects rotation of the cup, said cup having a port in its end and alternately registering with the intake and exhaust ports in timed relation with the reciprocation of the piston.

3. Apparatus of the type described including a cylinder, a piston slidably received in the cylinder, a crank shaft having an extra wide connecting rod bearing, a block slidably and rotatably carried on the bearing, a pin rigidly secured to the piston and rotatably secured to the block, cam and cam way means between the piston and cylinder for rotating the piston when the piston is reciprocated by the crank shaft, a head on the cylinder having intake and exhaust ports therein, a cup supported between the head and cylinder for rotary but non-axial movement, the inside of the cup forming a continuation of the bore of the cylinder and slidably receiving the head end of the piston, means connecting the piston and cup so that rotation of the piston effects rotation but non-axial movement of the cup, said cup having a port in its end and alternately registering with the intake and exhaust ports in timed relation with the reciprocation of the piston.

4. Apparatus of the type described including a cylinder, a piston slidably received in the cylinder, means for simultaneously rotating and reciprocating the piston in the cylinder, a head on the cylinder having intake and exhaust ports therein, a cup supported between the head and cylinder for rotary but non-axial movement, the inside of the cup forming a continuation of the bore of the cylinder and slidably receiving the head end of the piston, means connecting the piston and cup so that rotation of the piston effects rotation but non-axial movement of the cup, said cup having a port in its end and alternately registering with the intake and exhaust ports in timed relation with the reciprocation of the piston.

5. The combination defined in claim 4 wherein the cup is rotatably received in a counterbore in the head end of the cylinder.

6. The combination defined in claim 4 wherein the means for effecting rotation of the piston includes a cam track extending around the piston, and a roller cam engaging in the track and rotatably supported in a plug threaded into the cylinder.
